CLAIM

We claim the ornamental design for a code reader, as shown and described.

DESCRIPTION

FIG. 1 is a perspective view of the code reader, particularly showing the inventive design thereof;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken-lines in the views are for illustrative purposes only and form no part of the claimed design.
